ATTYS -

UNITED STATES PATENT OFFICE.

THOMAS ALFRED ABBOTT, OF LOWELL, MASSACHUSETTS.

DESIGN FOR AN EASEL.

SPECIFICATION forming part of Design No. 17,396, dated June 21, 1877.

Application filed March 23, 1877. Serial No. 232,200. Term of patent 7 years.

To all whom it may concern:

Be it known that I, THOMAS ALFRED ABBOTT, of Lowell, in the county of Middlesex, State of Massachusetts, have invented and produced a new and original Design for Easels, of which the following is a full, clear, and exact description, reference being had to the accompanying drawing, forming part of this specification, in which the single figure of the drawing is an isometrical perspective view of this newly-designed easel.

This design for easels consists, essentially, of an easel-body in imitation of a toboggan-sled in an inclined position, the curved nose of the sled being at the upper end of the body, and an inclined standard in contact at its upper end with said body, the said standard diverging downward at an angle to said body from its point of contact therewith.

In the drawing, A represents the body of the easel, which is the form of a toboggan-sled, the curved nose B of the toboggan forming the top of the easel. This body is disposed in an inclined position, and a standard, B, in contact at its upper end with said body at the rear thereof, diverges downwardly at an angle

to said body from its point of contact therewith.

The face of the body B has outwardly-projecting studs d near its edges, and said body 30 is preferably provided with a guide-rail, C, parallel with said edges, in contact with said studs. The rods m extend outward from the body to the inner edge of the curved nose B, and the upper ends of the guide-rail C form 35 contact with these rods.

I claim—

The ornamental design for an easel, as herein shown and described, consisting of an easel-body in imitation of a toboggan sled in an inclined position, the curved nose of the sled being at the upper end of the body, an inclined standard in contact at its upper end with said body, the said standard diverging downward at an angle to said body from its point of contact therewith, a guard-rail in front of said body near the edges thereof, and studs extending from said guard-rail to said body. 45

THOMAS ALFRED ABBOTT.
